UNITED STATES PATENT OFFICE

CHARLES H. SMITH, OF GREENVILLE, MICHIGAN, ASSIGNOR TO GIBSON REFRIGERATOR COMPANY, OF GREENVILLE, MICHIGAN, A CORPORATION OF MICHIGAN

EVAPORATOR

Application filed March 2, 1931. Serial No. 519,377.

This invention relates to refrigerator evaporator units and more particularly to units including a shaped coil of copper tubing, a plurality of plates, and supporting elements.

5 An object of this invention is a novel form of unit including a plurality of apertured plates having rearwardly extending portions which form an interior lining for the coil and which may be lapped to form a plate assembly. If desired, the bottom lining may be ridged to space the tray resting thereon from the lining. Further, the upper edges of the plates may be notched to permit a cross over connection being run from

10 one loop to the next, as desired.

Further objects will readily occur to those skilled in the art upon reference to the following description and the accompanying drawings in which

15 Fig. 1 is a front view of the evaporator.

Fig. 2 is a perspective diagrammatic view of the plate assembly.

Fig. 3 is a top plan view of the evaporator.

Fig. 4 is a side view of the evaporator.

20 Referring to the drawings, it will be seen that the evaporator includes a plurality of sheet metal plates, a shaped coil of copper tubing, and supporting elements.

25 *The plates*

The plate assembly includes a front plate 10, intermediate plates 12, and a back plate 14. The front plate and the intermediate plates are apertured as at 16, and the metal 30 which occupied the apertures is bent backwardly, on the top and bottom edges of the apertures, to form extending portions 18 and 20 which may be lapped onto and telescoped into one another, as shown. The edges of portions 18 and 20 of the rearwardmost of the intermediate plates are bent towards each other, as at 22, to form lugs to which may be securely attached the back plate 14, that the plates may be considered as forming a 35 unitary assembly.

Auxiliary plate assembly parts include a pair of channels 24, and a pair of straps 26, all of which connect the plates and extend from the front plate 10 to the rear plate 14.

40 The channels 24 form rails upon which the

edges of the ice tray 28 may slide and be supported, and the overlapping portions 20 are ridged at 30 to form supports upon which the ice tray 32 may slide and be supported, out of contact with the major part of the 45 portions 20, as indicated.

The upper edges of the intermediate plates 12 have wide shallow notches 34 which permit the copper tubing of the coil to be described below, to cross on the upper side of 50 the coil from one loop to the next adjacent loop, and in this fashion the upper surface of the coil is disposed below the upper edges of the plates.

55 *The coil*

The coil 40 is formed of a continuous length of copper tubing, shaped to form substantially rectangular loops 42 which surround the portions 18 and 20 of the plates, 60 the loops being connected to one another by the cross over loop portions which run from the upper left part of a front loop to the upper right part of the next rearward loop, some of the cross overs being thru the notches 65 34 in the intermediate plates. As indicated, there are three loops between each pair of plates, although this number may be varied as desired. For example, there might well be only one loop between each pair of plates, 70 the plates being, in any case, in the spaces between adjacent loops.

75 The coil inlet 46 leading from the expansion valve rises and runs over the top of the loops to the upper right part of the forwardmost loop, and the coil outlet 48, runs over the top of the loops from the upper left part of the rearwardmost loop, to the suction side of the compressor, not indicated.

80 The loops are soldered to the plates at their contacting surfaces, and the interior of the loops are protected from the trays, by the lapping portions 18 and 20 which form a continuous lining for the coil, and by the channels 24 and the straps 26. Further, the loops 85 are within the edges of the plates so that the latter protect the outside of the coil as well.

90 While the coil has been disclosed and described as a continuous coil of tubing, it 95 might well be made of a plurality of U tubes 100

connected by headers, or by **U** sheets, grooved to resemble tubes, and connected by headers.

being inside the coil, and having spaced ridges thereon for purposes described.

The supports

The coil and plate assembly, as a unit may be supported from the under surface of a horizontal wall of a cabinet by means of bolts, not shown, pass thru the apertures 50 in the wings 52 of the U straps or brackets 54 disposed under the horizontal run parts of the inlet 46 and outlet 48 of the coil and soldered to the upper parts of the coil loops. Further, the coil support may be strengthened by means of bolts 56 connecting straps 58 under the loops with angles 60 secured or soldered to the straps or brackets 54, as indicated.

20 An expansion valve support may be provided and the latter may include an angle 62 soldered or otherwise secured to the back plate 14.

It will be seen that there has been provided an evaporator unit comprising a continuous coil of copper tubing, lined on the inside and protected inside and out by plates, etc., and having suitable supporting means.

Now having described the invention and the preferred embodiment thereof, it is to be understood that the said invention is to be limited, not to the specific details herein set forth, but only by the scope of the claims which follow.

2nd What I claim is:

35 1. An evaporator unit comprising a coil of tubing having an inlet and outlet, and a plurality of sheet metal plates disposed between and secured to spaced loops of the coil, certain of the plates having rearwardly extending portions engaging portions of the next hindmost plate whereby the plates may be secured to one another to form an integral unit, the rearwardly extending portions being inside the coil.

45 2. An evaporator unit comprising a coil of tubing having an inlet and outlet, and a plurality of sheet metal plates disposed between and secured to spaced loops of the coil, certain of the plates having rearwardly extending portions engaging portions of the next hindmost plate whereby the plates may be secured to one another to form an integral unit, the rearwardly extending portions being inside the coil, and overlapping to form a smooth interior lining wall for the coil upon which can rest an article to be refrigerated.

60 3. An evaporator unit comprising a coil of tubing having an inlet and outlet, and a plurality of sheet metal plates disposed between and secured to spaced loops of the coil, certain of the plates having rearwardly extending portions engaging portions of the next hindmost plate whereby the plates may be secured to one another to form an integral unit, the rearwardly extending portions

4. An evaporator unit comprising a coil of tubing having an inlet and outlet, and a plurality of sheet metal plates disposed between and secured to spaced loops of the coil, certain of the plates having notches in their edges to permit the tubing to cross the plates from one loop to the next, certain of the plates having rearwardly extending portions engaging portions of the next hindmost plate whereby the plates may be secured to one another to form an integral unit.

5. An evaporator unit comprising a coil of tubing having an inlet and outlet, and a plurality of sheet metal plates disposed between and secured to spaced loops of the coil, certain of the plates having notches in their edges to permit the tubing to cross the plates from one loop to the next, certain of the plates having rearwardly extending portions engaging similar portions of the next hindmost plate whereby the plates may be secured to one another to form an integral unit. 80

6. An evaporator unit comprising a coil of tubing having an inlet and outlet, and a plurality of sheet metal plates disposed between and secured to spaced loops of the coil, certain of the plates having notches in their edges to permit the tubing to cross the plates from one loop to the next, certain of the plates having rearwardly extending portions engaging portions of the next hindmost plate whereby the plates may be secured to one another to form an integral unit, the rearwardly extending portions being inside the coil.

7. An evaporator unit comprising a coil of tubing having an inlet and outlet, and a plurality of sheet metal plates disposed between and secured to spaced loops of the coil, certain of the plates having notches in their edges to permit the tubing to cross the plates from one loop to the next, certain of the plates having rearwardly extending portions engaging portions of the next hindmost plate whereby the plates may be secured to one another to form an integral unit, the rearwardly extending portions being inside the coil and overlapping to form a smooth interior lining wall for the coil upon which can rest an article to be refrigerated. 110 115

8. An evaporator unit comprising a coil of tubing having an inlet and outlet, and a plurality of sheet metal plates disposed between and secured to spaced loops of the coil, certain of the plates having notches in their edges to permit the tubing to cross the plates from one loop to the next, certain of the plates having rearwardly extending portions engaging portions of the next hindmost plate whereby the plates may be secured to one another to form an integral unit, the rearwardly extending portions being inside the coil and overlapping to form a smooth in- 130

terior lining wall for the coil upon which can rest an article to be refrigerated, and having spaced ridges thereon for purposes described.

- 5 9. An evaporator unit comprising a coil of tubing having an inlet and outlet, and a plurality of sheet metal plates disposed between and secured to spaced loops of the coil, certain of the plates having rearwardly extending portions engaging portions of the next hindmost plate whereby the plates may be secured to one another to form an integral unit, the rearwardly extending portions being inside the coil, and overlapping to form
- 10 15 a smooth interior lining wall for the coil upon which can rest an article to be refrigerated, and having spaced ridges thereon for purposes described.

- 10. An evaporator unit comprising a coil of tubing having an inlet and an outlet, and a plurality of sheet metal plates disposed between spaced loops of the coil, certain of the plates having rearwardly extending portions inside the coil, said portions extending
- 20 25 to and coacting with corresponding portions on the next adjacent plate to form a functionally continuous wall.

- 11. An evaporator unit comprising a coil of tubing having an inlet and outlet, and a plurality of sheet metal plates disposed between spaced loops of the coil, certain of the plates having rearwardly extending portions engaging portions of the next hindmost plate whereby the plates may be secured to one
- 20 35 another to form an integral unit, the rearwardly extending portions being inside the coil.

In testimony whereof, I sign this specification.

40 CHAS. H. SMITH.
